Inventor:

Louis H. Marston

Attest,

UNITED STATES PATENT OFFICE.

LOUIS H. MARSTON, OF CHICAGO, ILLINOIS, ASSIGNOR TO THE TONK MANUFACTURING COMPANY, OF SAME PLACE.

DESIGN FOR A PIANO-STOOL.

SPECIFICATION forming part of Design No. 21,667, dated June 28, 1892.

Application filed December 15, 1891. Serial No. 416,191. Term of patent 3½ years.

To all whom it may concern:

Be it known that I, LOUIS H. MARSTON, a citizen of the United States, residing at Chicago, Illinois, have invented and produced a new and original Design for Piano-Stools, of which the following is a specification, reference being had to the accompanying drawing.

The drawing is a perspective view.

The leading feature of my design consists in a circular seat and cap-piece and base, the base and cap-piece being joined by a cylindric pedestal having a flaring base and supporting-legs, the upper portions of which represent intertwined spirals, while their lower portions represent a claw grasping spheres.

A represents the seat, which is of circular outline, having its edge beaded.

B represents the cap-piece, also of circular outline, with a raised center b.

D represents the pedestal, which is substantially cylindrical in outline, the lower end being expanded into a series of circular bands, and E represents the base, which is also circular in outline with beveled beaded margins e e.

F represents the legs, the upper portions of which present a series of intertwined relief spirals or rope-work, while their lower ends have conical portions f, terminating in the conventional claw f', grasping the spheres F'.

I claim—

The design for piano-stools, substantially as herein shown and described.

LOUIS H. MARSTON.
